RADIATOR

Leopold Lithman, New York, N. Y.

Application March 7, 1932. Serial No. 597,105

4 Claims. (Cl. 219—38.7)

The object of my invention is to provide a radiator which is preferably formed of heat conducting metal and provided with steam chambers and air flues in juxtaposition so that air may rise through the radiator and be heated. This and other objects are accomplished by my invention, one embodiment of which is herein-after more particularly set forth.

For a more detailed description of my invention, reference is to be had to the accompanying drawing, forming a part hereof, in which

Figure 1 is a side elevation of my invention, partially in section;

Figure 2 is a sectional plan view of the same; 15 Fig. 3 is a perspective view of one of the steam chambers, and Fig. 4 is a perspective view of one of the air tubes with its lower end held uppermost to show the screw holes through which screws extend to fasten it to one of the 20 steam chambers.

Throughout the various views of the drawing, similar reference characters designate similar parts.

My improved radiator 1 may be mounted on 25 a base 2 which, in the present embodiment, is also mounted on casters 3, although it may be mounted in any suitable manner, and this base is provided with an electric heater 4, which, at its outflow end, has a vertically disposed pipe 5 which is connected to the steam chambers 6 and 7 by suitable fittings. These chambers are composed of a series of castings 8 with top and bottom flanges 9, and internal chambers 10 through which the steam passes. These chambers 35 surround the flanges 9, and to these flanges are secured the tubes 11, which form air flues for the passage of air, which is heated by steam in the chambers 10. Adjacent castings are connected by short nipples 12 in the manner indicated. As many of these castings and tubes may 40 be used as desired, and at the end remote from the pipe 5 is a return pipe 13 through which the cooled steam or water of condensation may pass to the horizontal pipe 14 which returns the 45 cooled fluid to the heater 4 where it is re-heated. A valve 15 may be put in the pipe 13 so as to shut off the upper chamber 7, should such be desired.

The tubes 11 are sheet metal and preferably 50 made of copper, and are provided with holes 16 (shown in Fig. 4) through which screws are passed in the corresponding holes 17 in the flanges 9.

In view of the foregoing, the operation of my 55 radiator will be readily understood.

Let it be assumed that sufficient water is in the apparatus, and that a power is turned on to the heater 4. Under such circumstances, water in the heater will be expanded and may be 60 converted into steam according to the tempera-

ture of the heater, but whether steam or water, the heated product passes upwardly through the pipe 5 into the steam chambers 6 and 7, whence it passes as above described. After heating the flues 11, air rising through these 65 flues is also heated whereby the water is condensed or cooled and returns to be re-heated.

While I have shown and described one embodiment of my invention, it is obvious that it is not restricted thereto, but that it is broad 70 enough to cover all structures that come within the scope of the annexed claims.

Having thus described my invention, what I claim is:

1. A radiator having a water-receiving chamber, an electric heater disposed in said chamber for heating the water contents, pipes extending from the opposite ends of the water chamber, spaced groups of connected steam boxes extending between and joining the pipes, each of the 75 steam boxes having a central passage extending through it, the passage being open at both of its ends, the opposite ends of said passage terminating in flanges extending from the box and pipes connecting one flange of each box in 80 one group with a flange on each box in the other group.

2. In a radiator, a hollow steam box having entrance and exit openings for steam, a central passage extending through the box and open 90 at both of its ends but closed to the interior of the box, the ends of said passage terminating in flanges which project beyond the ends of the box, and pipes fitted over the flanges and projecting therefrom.

3. A radiator composed of, several groups of steam boxes, the boxes in each group being connected together with nipples, each box having a steam chamber and an air passage extending through said chamber but closed to it, the air 100 passage being open at both of its ends, pipes extending between and connecting one end of the air passages in one group of steam boxes with one end of the passages in the other group, and steam inlet and outlet pipes connecting the two 105 groups of boxes.

4. A radiator composed of an upper group of steam boxes and a lower group spaced from the upper group, each box in each group being formed with a steam chamber and an air passage closed to said chamber, the steam chambers in the steam boxes in one group being in communication with those in the other group only at the ends of the groups, air pipes extending between and connecting the boxes of the two groups, and air pipes fitted to and extending above the tops of the boxes in the upper group.

LEOPOLD LITHMAN.
